UNITED STATES PATENT OFFICE

171,672

INSULATOR FOR WIRE FENCES

Joyce C. Verplank, Ellendale, Minn., assignor to
North Central Plastics, Incorporated, Ellen-
dale, Minn., a corporation of Minnesota

Application July 24, 1953, Serial No. 26,128

Term of patent 14 years

(Cl. D26—10)

To all whom it may concern:

Be it known that I, Joyce C. Verplank, a citizen of the United States, residing at Ellendale, county of Steele and State of Minnesota, have invented a new, original, and ornamental Design for an Insulator for Wire Fences, of which the following is a specification, reference being had to the accompanying drawing, forming a part thereof.

Figure 1 is a top view of an insulator for wire fences, showing my new design;

Figure 2 is a side elevational view thereof;

Figure 3 is a bottom view thereof;

Figure 4 is a rear view thereof; and

Figure 5 is a front end view thereof.

The dominant features of my design reside in those portions shown in full lines.

I claim:

The ornamental design for an insulator for wire fences, substantially as shown and described.

JOYCE C. VERPLANK.
